WORLD WAR GAME

David Cohen, New York, N. Y.

Refiled for abandoned application Serial No. 246,351, December 17, 1938. This application August 7, 1940, Serial No. 351,687

4 Claims. (Cl. 273—134)

This invention relates to new and useful improvements in a war game board device. The present application is a refile of my abandoned application, filed on December 17, 1938, Serial Number 246,351.

The invention has for an object the construction of a device as mentioned which is characterized by a flat board imprinted with war game areas and indices which are associated with perforations through the board in a particular manner.

More specifically, the invention contemplates the provision of a means for supporting the board in a slightly elevated position to provide a space beneath the board, and proposes the use of tooth picks, movable members symbolizing soldiers, civilians, guns, ammunition or any other figures engaged through the perforations and movable to other perforations and used for the playing of the game according to predetermined rules.

Still further the invention proposes the use of a spinable pointer mounted on the top center of the board and usable during the playing of the game.

Another object of the invention resides in a novel arrangement whereby the locations of the movable members are used to assist in controlling the spinning of the pointer.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a device constructed according to this invention.

Fig. 2 is a vertical sectional view taken on the line 2—2 of Fig. 1.

Fig. 3 is a fragmentary enlarged plan view of one corner of the device.

Fig. 4 is a fragmentary sectional view taken on the line 4—4 of Fig. 2.

Fig. 5 is a front elevational view of one of the movable members used in the game.

Fig. 6 is a front elevational view of another form of movable members.

Fig. 7 is a perspective view showing the game board on a folding table.

Fig. 8 is a perspective view of a plurality of play discs used in playing the game.

Fig. 9 is a perspective view of one of the discs in reversed position.

The war game board device, according to this invention, includes a flat board 10 associated with a support for supporting the board in a slightly elevated position to provide a space 11 beneath the board. The supporting means consists, essentially, of flange portions 12 bent from the edge portions of the board and extended downwards and adapted to rest upon the top of a table or other flat surface. The top face of the board 10 is imprinted with a plurality of war game areas and indices which are associated with perforations 13 formed through the material of the board. A spinable pointer 14 is mounted upon the top center of the board and is adapted to point to the areas and indices mentioned.

A group of movable members 15 is provided with the game and are adapted to be inserted through the perforations 13 to be maintained in upright positions. These movable members may be shifted from certain of the perforations to other of the perforations according to rules and regulations of the game.

The war areas and indices are arranged about a rectangular square blank area 16. The pointer 14 operates within this blank area 16. The pointer is mounted on a spindle 17 which extends through the center of the flat board and downwards into the space 11. Surrounding the central area 16 there are several surrounding area strips 18, 19, 20 and 21. These strips are imprinted with the names of war equipment such as various types of ammunition, guns, airplanes, cruisers, tanks, symbols of men, etc. In Fig. 3 an enlarged detailed view of one corner of the board has been shown to give a better idea of the imprinted matter.

The outermost area 21 is imprinted with the slogan "No man's land." This area is provided with some of the perforations 13 for holding some of the movable members. The movable members are intended to represent men, munitions and symbols of all types, and when there are movable members in this area the indication is that the men are in "No man's land." In one of the corners of the area 20 there is a circle 23 imprinted with the names of various cities. Adjacent the name of each city there is a perforation 13 to represent the particular captured, advanced, destroyed or surrounded cities. To the sides of the circle 23 there are perforated areas 13 for receiving the movable members representing submarines, indicated by the name 24, an area for cruisers 25, torpedoes 26, men on reserve 27, etc. There are areas representing front and rear lines

28 and 29, respectively. There are a plurality of other areas representing lines of attacks, designating front and rear attacks of towns, planes, and other data. The different corners of the board are arranged to represent different countries.

On diametrically opposite sides of the board 10 there are auxiliary projecting board portions 30 which comprise score boards. These score boards are preferably detached from board 10 and are tabulated with material to assist in keeping the score of the war game. The score board 30 is also provided with perforations 13 for movable members to represent various points used in the game. One of the rules for scoring will be given in this specification since it is feasible to use various rules with the war game board device. The rules may provide for two players, three or four players, although four players are preferable since they attack from both the front and rear; but 6 or 8 persons can also play the game. When taking partners, one side attacks the front and the other attacks the rear. It is advisable to spin for this choice. These are the allies of other countries in the said game with provisions of an extra outlay for the additional four partners according to the necessity of the said game so that eight players can play the game.

An arrangement is provided for influencing the spinning of the pointer 14, depending upon positions of certain of the movable members 15. This arrangement includes several slightly flexible discs 33, 34, 35, etc., of different sizes superimposed one above the other with the small discs arranged at the top. These discs are coaxially attached on the spindle 17 at different distances from the board 10. Each of the discs is formed with niches 36 arranged in various spaced relations with respect to each other. This arrangement permits a free uninterrupted spinning motion of the pointer 14 and prevents the pointer from stopping at the same position.

Each of the perforations 13 is formed by stamping the material of a flat board upwards so that there are small projecting prongs capable of assisting in supporting the movable members in a vertical position. During the playing of the game the movable members 15 will be moved according to predetermined rules, and when movable members are placed so as to rest against the top faces of the discs 33, 34 and 35 they will influence the stopping of the pointer. For example, when the inner end of a movable member rides into one of the niches 36 there will be a tendency for the pointer to come to a stop at this position, particularly if the pointer has lost most of its turning force and is near a stop anyway. Of course, the movable members will not positively be able to stop the rotations of the pointer and this causes the element of chance to enter as to just where the pointer will stop.

In Fig. 5, the movable member 15' symbolizes a soldier and in Fig. 6 the movable member 15'' is in the form of an anti-aircraft gun.

In Fig. 7, the game board 10 forms a part of or is secured to a table which may be in the form of a foldable or bridge table with collapsible legs 10'.

In Figs. 8 and 9 discs 40 are illustrated with numerals from 1 to 10 at their faces 40^a. These discs are stacked with their faces 40^b down so that the numerals shall not be visible at their other faces 40^a. Each of these discs 40 may be

used to designate the amount of men killed, captured, and surrendered. Disc #1 would represent 1000 men; disc #2 would represent 2000 men; and so on up to disc #10 which represents 10,000 men.

As the game is played and the pointer 14 is spun, the location indicated by the pointer, when the latter comes to a stop, designates the motion of the moving members and the uppermost disc 40 designates the number of men killed, captured or surrendered.

It is to be understood that the board and the various parts may be made of any suitable material, such as cardboard, composition, etc., and may be colored as desired.

The game may be played as follows:

Spin pointer for partners, pointer showing Front and Rear. When two players play, spin to indicate who should attack first. The First

20 attacks the Front first and the Rear last. When four players play, spin for partners, then the pointer showing "Front" for the first two players become partners who play against the remaining two players. Then the four players 25 may shoot in both directions, Front and Rear. When the partners take their position to commence playing, the circle with the word "Front" before it must face them. Then partners are chosen and the front attacks first, and the rear last. At all times, each player moves his own men and guns and keeps his own score board. The above rule applies for two or four players.

For six or eight players: The partners can move or use one another's men, or ammunition, or may keep the score board.

For eight players: First four players, showing Front, take their position or seat where the circle faces the word Front, and the remaining four players attack at rear only, throughout the game, whenever the pointer shows rear. They also take the same position. Each and every player, following his turn, attacks in rotation.

When six players play, four attack at front, other two partners attack at rear only. Otherwise the same rules apply as for eight players. To start the game, place the men and guns:

1. Front line, men and all guns
2. Rear line, men and all guns
3. Men on reserve, men and all guns
4. No man's land, men and all guns

To attack: At the pointer showing captured men, there will be 10 cards or discs, namely a war chest. The player will pick up one of these cards or discs on which certain numbers will be written. This number will indicate how many men one will take off and is given to the player as "prisoners." Then, same player continues the attack.

The same rule follows when the pointer shows "Men killed," "Continued attack," and when the pointer indicates "Surrender men" the attack is stopped but the same rules will apply as above.

At "Advance," the players move up men or guns and continue to attack. At all times, the front and rear lines must be occupied with men and guns. If the attack is a rear attack, remove men or guns from the rear, and if it is a front attack remove men or guns from the front line.

At "Retreat," the player gives up the attack and moves back men or guns. It is not necessary to move all men or guns. In an "Air raid," the player follows the circle; in this circle you have cities marked 1 to 9 front, and 1 to 9 rear.

When the player "Attacks" at the rear and the pointer shows the captured town, the player places one of his own men in the player's circle one plays against, marked No. 1, Rear and continues the attack. Should the pointer appear again at the same marking, place a man at marking No. 2 Rear, and so on, all through the game.

When the player attacks at "Front," the player places his men in the front, in the same circle and in the same manner. In this same circle, there is a straight line of perforations extending diametrically through the center of the circle indicating destroyed cities. Should the pointer indicate "Destroyed town," the player's man is placed in one of those holes where the name of the country is marked, and the attack may then be continued. Should the pointer indicate "Surrender town," the player who holds captured towns covered, takes off a man, and gives up the attack. Should the player have no town captured, he gives up the attack in the usual manner. Should the pointer indicate "Advance town," the player places a man in, and continues the attack, moves up his reserve, advances his fleet, advances his planes, and advances his cavalry. It is not necessary to move all guns or men but move one or as many as the player may desire and continue the attack.

In the artillery, H. & L. indicates Heavy and Light guns.

When the pointer shows "Captured gun": The player gets a gun from the man he plays against. The same applies for planes, submarines, cruisers, torpedoes, and continues attack. The player places them in his score board at the mark "Captured." All captured guns can be used from the player's score board.

Should the pointer indicate destroyed gun, plane, submarine, torpedoes, or cruisers, the player receives from his opponent whatever the pointer indicates. Then continue the attack, and place the gun marked destroyed on his score board.

Should the pointer indicate surrender gun, plane, submarine, torpedo or cruiser, the player loses the indicated object. The player also stops the attack if the pointer indicates "Retreat gun." Then the player moves back a gun and gives up the attack. At all times the player must be alert to all attacks, moves of men and guns. The game is over when a player has lost all men, all guns or all towns marked "Captured" on the map, which is the circle.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a flat game board having a plurality of perforations formed around the edge thereof, means for supporting said board in a slightly elevated position to provide a space beneath said board, a spinnable pointer mounted on the top center of said board, a spindle having said pointer fixedly mounted on one end thereof and having its other

end rotatively extended through said board and into said space, discs of various sizes coaxially fixedly mounted on said spindle within said space and at varying distances from the bottom face of said board, movable members having their bottom ends passed through said perforations and into said space to contact the faces of said discs, and said discs being formed with a plurality of niches into which the bottom ends of said members frictionally engage as said pointer rotates for retarding the spinning thereof and to influence its stopping position.

2. In a device of the class described, a flat game board having a plurality of perforations formed around the edge thereof, means for supporting said board in a slightly elevated position to provide a space beneath said board, a spinnable pointer mounted on the top center of said board, a spindle having said pointer fixedly mounted on one end thereof and having its other end rotatively extended through said board and into said space, discs of various sizes coaxially fixedly mounted on said spindle within said space and at varying distances from the bottom face of said board, movable members having their bottom ends passed through said perforations and into said space to contact the faces of said discs, and said discs being formed with a plurality of niches into which the bottom ends of said members frictionally engage as said pointer rotates for retarding the spinning thereof and to influence its stopping position, said discs being arranged with the smaller ones positioned adjacent the bottom face of said board so that each of said discs will have an exposed peripheral area in which said niches are formed.

3. In a device of the class described, a flat game board having a plurality of perforations formed around the edge thereof, means for supporting said board in a slightly elevated position to provide a space beneath said board, a spinnable pointer mounted on the top center of said board, a spindle having said pointer fixedly mounted on one end thereof and having its other end rotatively extended through said board and into said space, discs of various sizes coaxially fixedly mounted on said spindle within said space and at varying distances from the bottom face of said board, movable members having their bottom ends passed through said perforations and into said space to contact the faces of said discs, and said discs being formed with a plurality of niches into which the bottom ends of said members frictionally engage as said pointer rotates for retarding the spinning thereof and to influence its stopping position, said discs being formed of flexible material so that said members may easily disengage from said niches to only retard the rotation thereof and not completely stop said rotations.

4. In a device of the class described, a raised game board having a plurality of perforations formed around the edge thereof, a spindle rotatively extended through said board, a pointer fixedly mounted on the top end of said spindle to rotate across the top face of said board, discs of varying sizes mounted on the bottom end of said spindle and spaced varying distances from the bottom faces of said game board, and members extendable through said perforations to frictionally bear against the top face of said discs to retard the free rotation of said spindle.

DAVID COHEN.
